CATALYTIC ALKYLATION OF ISO-PARAFFIN
WITH OLEFINSWright W. Gary, Los Angeles, Calif., assignor to
The M. W. Kellogg Company, Jersey City, N. J.,
a corporation of Delaware

Application November 26, 1941, Serial No. 420,511

7 Claims. (Cl. 260—683.4)

1

This invention relates to the alkylation of iso-butane with butylene in the presence of a catalyst, and more particularly to the preparation of mixtures of the latter hydrocarbons in their alkylate-forming proportions from certain random mixtures of the various iso- and normal C₄ paraffins and olefins.

As is well known, a high octane aviation fuel blending stock may be obtained by alkylating iso-butane with butylene in the presence of catalysts of the sulfuric acid type. In this reaction each mol of iso-butane apparently reacts with one mol of butylene, so that ideally the feed to the process should contain the iso-paraffin and olefin in equi-molal proportions. In practice, however, it is customary to obtain feed stocks for alkylation from natural gas and gasoline, refinery residue gases produced in oil cracking operations, and other sources in which not only is there rarely the ideal iso-paraffin/olefin ratio, but which almost invariably contain the non-alkylatable hydrocarbon, normal butane.

In many cases, of course, it is possible to combine C₄ fractions from different sources and having different iso-paraffin/olefin ratios to obtain an approximate balance. In numerous other cases, however, and most frequently when all the materials must be obtained from a single source, gross disparities in the available quantities of iso-butane and butylene are met with.

One of the objects of the present invention is to provide a method of preparing a feed stock for alkylation having a balanced iso-butane/butylene ratio from a mixture of C₄ hydrocarbons wherein there is a deficiency of butylene.

Another object of the invention is to provide a process whereby an alkylation feed stock may be prepared from normal butane. Other objects and advantages of the invention will appear during the course of the description hereinafter given.

In order to achieve the above and related ends it is contemplated by the invention to convert normal butane into iso-butane by catalytic isomerization, and then to convert iso-butane into butylene by non-catalytic pyrolysis, or what might be called purely thermal dehydrogenation. I have found that whereas at best a yield of butylene of only 20 to 25 per cent is obtainable in pyrolyzing normal butane, iso-butane may be thermally dehydrogenated to yield as much as 60 per cent of butylene. The combination of an isomerization step with a pyrolysis step thus affords a route whereby butylene deficiencies may be made up at the expense of the normal butane,

which otherwise could not be used efficiently for the production of alkylate.

In the event that the quantity of butylene obtainable from normal butane in accordance with the invention is still not sufficient to effect an iso-butane/butylene balance when combined with alkylation reactants already available, I may subject a sufficient quantity of the excess iso-butane to pyrolysis along with the iso-butane obtained from normal butane, and thereby correct even the most disparate iso-butane/butylene ratios. If on the other hand there is more than enough normal butane to produce the butylene required to balance the available quantity of iso-butane, I may withhold from the pyrolysis step a portion of the iso-butane produced by isomerization, the withheld portion being of sufficient size to bring into balance the final overall iso-butane/butylene ratio.

20 An exemplary embodiment of the invention will now be described in detail and suitable conditions of operation will be given for the several conversion stages involved, the description being with reference to the annexed drawing. The drawing is a schematic flow sheet wherein unitary processing stages are conventionally designated for greater clarity by rectangular blocks bearing identifying legends.

In the drawing, the alkylation step 2 comprises 30 conventional catalytic iso-butane-butylene alkylation in the presence of a catalyst such as 96% sulfuric acid, followed by fractionation of the product into alkylate and unreacted iso-butane and normal butane. The presence of unreacted iso-butane in the alkylation product arises from the fact that the alkylation reaction is preferably carried out with about 5 to 8 mols of iso-butane present per mol of butylene. The excess iso-butane influences the course of the 35 alkylation reaction without actually taking part in it, and is withdrawn unchanged in the product mixture. After being separated from the alkylate and from normal butane this excess iso-butane, or an equivalent amount taken from some other source, must be returned to the alkylation zone 40 to maintain the desired iso-butane/olefin ratio therein. The latter ratio is not to be confused with the 1:1 ratio in which the two reactants actually combine.

45 The isomerization step 6 is likewise a conventional operation comprising the contacting of normal butane with a suitable catalyst such as aluminum chloride. I prefer to employ with the latter catalyst an isomerization temperature between about 125° F. and 250° F. and a pressure

high enough to maintain the reactant material in the liquid phase. The activity of the catalyst may be enhanced if desired by adding dry hydrogen chloride to the feed.

The isomerization reaction is not productive of high yields of iso-butane in one catalytic contact, and the isomerization product will contain ordinarily from about 40 to about 75 per cent of normal butane, depending upon the time of contact with the catalyst. In view of the practical absence of side-reactions, however, it becomes possible to obtain an ultimate yield of iso-butane of substantially 100 per cent by returning unreacted normal butane for further contacting with the catalyst. As will be hereinafter explained, complete conversion of normal butane to iso-butane is accomplished in accordance with the invention. For purposes of illustration, however, it will be assumed that the partially converted mixture obtained from the isomerization step 6 contains 40 per cent iso-butane and 60 per cent normal butane.

The pyrolysis step 9 is accomplished by heating iso-butane, suitably in a pipe coil or conventional tubular furnace, to approximately 1000° F. to 1100° F., and maintaining it at the elevated temperature for a brief period.

The yield of butylene which will be obtained by this pyrolysis is chiefly determined by the operating pressure and by the length of time that the reactant material is maintained at the conversion temperature. The highest ultimate yields, ranging up to 60 per cent or better, are obtained at atmospheric pressure and with a relatively short conversion time. In order to reduce the requisite furnace tube volume, however, it will usually be more economical to employ a pressure of 100 to 200 pounds per square inch. The pyrolysis reaction is like the isomerization reaction in that complete conversion is not effected in a single pass through the conversion zone. It is unlike the isomerization reaction in that side-reactions result in the formation of appreciable quantities of C₃ and lighter hydrocarbons. The pyrolysis step 9 shown in the drawing includes removal of the light by-products from the product butylene and unconverted iso-butane, but not the separation of the latter two constituents. The highest ultimate yields of butylene are obtained in a short time, high recycle ratio operation wherein the yield per pass is relatively low; 20 per cent per pass is a suitable figure and will be assumed herein for illustrative purposes.

An ultimate yield of butylene of approximately 50 per cent is readily obtainable in the pyrolysis step and will be assumed for the purpose of the present example. The return of unconverted iso-butane to the pyrolysis step is indirect and will be understood from the description hereinafter given.

It will be assumed further for illustrative purposes in the example hereinafter described that a mixture of C₄ hydrocarbons, such as might be separated from the by-product gas produced in cracking petroleum oils, is available as the net alkylation feed stock and that the relative proportions of the C₄ hydrocarbons are as follows: Normal butane, 50 mols; iso-butane, 30 mols; and butylene, 20 mols; total, 100 mols.

In the drawing, the above described C₄ mixture is supplied to alkylation process 2 as indicated by line 1; there is simultaneously supplied to the process 50 mols of iso-butane and 75 mols of normal butane through line 8, and 20 mols of

butylene and 60 mols of iso-butane through line 12. Also, 100 mols of iso-butane are supplied through line 11. The gross feed therefore consists of iso-butane, 240 mols; butylene, 40 mols; and normal butane, 125 mols; total, 405 mols.

In the alkylation reactor, the 40 mols of butylene react with 40 mols of iso-butane to form alkylate, leaving 200 mols of iso-butane and 125 mols of normal butane unreacted. The alkylate is separated by fractionation and disposed of as desired, as indicated by line 3.

The 125 mols of normal butane are likewise separated and transferred via line 4 to the isomerization step, wherein 50 mols (40 per cent) thereof are converted into iso-butane. The isomerization product, consisting of this 50 mols of iso-butane plus the remaining 75 mols of normal butane, is returned via line 8 to the alkylation reactor to make up a portion of the gross feed thereto.

The 200 mols of iso-butane in the alkylation product is separated by fractionation and after withdrawal as indicated by line 5 is subdivided into two portions. The first, consisting of 100 mols, is returned immediately to the alkylation process via line 11 to maintain the desired iso-butane/butylene ratio of 6:1 (240 mols iso-butane/40 mols butylene) in the alkylation zone.

The second portion of 100 mols is transferred as indicated by line 10 to the pyrolysis step wherein, in one pass, yields of 20 mols of butylene and 20 mols of light gaseous by-products are obtained by the conversion of 40 mols of the iso-butane, 60 mols remaining unaffected. After separation and disposal of the by-products through line 7, the mixture of 60 mols of iso-butane and 20 mols of butylene is returned as indicated by line 12 to the alkylation step.

It will be seen that the quantities of materials charged to the individual steps and to the combined system are in balance with the intermediate and final products. It will also be seen that in this embodiment of the invention, the recycling of unconverted normal butane and iso-butane to the isomerization and pyrolysis steps, respectively, is by way of the alkylation step, wherein removal of the respective conversion products is effected through the agency of the alkylation reaction. Although I prefer to accomplish recycling in this way, it will be understood by those skilled in the art that, if desired, pure iso-butane and butylene could be returned to the alkylation step through lines 8 and 12 respectively, instead of partially converted mixtures, by augmenting the isomerization and pyrolysis steps each with its own individual fractionation system, whereby unconverted material could be separated for immediate recycling. In the latter event the quantity of iso-butane recycled through lines 5 and 11 for the benefit of the alkylation reaction would need to be increased, because of the absence of any iso-butane recycle in the butylene returned from the pyrolysis step. It will be further understood that a material balance such as that obtained in the example could as readily be reached assuming different yields per pass and ultimate yields, different proportions of constituents in the net feed, and other variations. Thus if there had been less than 15 mols of butylene in the assumed feed stock, then even the whole of the iso-butane (50 mols) produced by isomerization of the normal butane would not have yielded enough butylene on pyrolysis to make up the total of 40 mols needed to balance the 40 mols of iso-butane in the net feed, and a portion

of the iso-butane in the net feed would have had to be sent to the pyrolysis step. If on the other hand there had been more than the assumed amount of butylene in the feed stock, a smaller proportion of the total available iso-butane would have been pyrolyzed.

My invention is not limited by any of the illustrative examples herein, but only by the following claims.

I claim:

1. The method of preparing a high octane motor fuel from normal butane which comprises catalytically isomerizing normal butane to form iso-butane, pyrolyzing a portion of the thus-produced iso-butane to produce butylene, and catalytically alkylating thus-produced butylene with iso-butane produced in said isomerization step.

2. A method of preparing a high octane motor fuel from a mixture of iso-butane, normal butane and butylene, wherein there is less than an equimolar proportion of butylene relative to the iso-butane, which comprises adding butylene to the mixture and then subjecting the mixture to catalytic butylene-iso-butane alkylation, separating normal butane from the alkylation product and converting thus-separated normal butane into iso-butane by catalytic isomerization, pyrolyzing thus-produced iso-butane to produce butylene, adding thus-produced butylene to further quantities of said mixture to be alkylated as aforesaid, and repeating said sequence of steps.

3. A method of preparing a high octane motor fuel from a mixture of iso- and normal butane and butylene which comprises introducing said mixture into a catalytic alkylation zone, simultaneously introducing into said zone a second mixture consisting of normal and iso-butane and a third mixture consisting of iso-butane and butylene, catalytically alkylating iso-butane with butylene in said zone, withdrawing a product mixture of alkylate, iso-butane, and normal butane from said zone and fractionally distilling it to separate iso- and normal butane from alkylate and from each other, contacting the thus-separated normal butane with an isomerization catalyst to form a mixture of normal and iso-butane, returning said last-mentioned mixture to said alkylation zone as said second mixture aforesaid, subjecting iso-butane separated from said product mixture to pyrolysis to convert it partially into butylene and lighter by-products, separating said by-products from butylene and unconverted iso-butane, and returning a mixture of said latter two materials to said alkylation zone as said third mixture aforesaid.

4. In a process for alkylating iso-butane with butylene in an alkylation step in which iso-butane is maintained in substantial excess over butylene in a liquid acid catalyst alkylation zone and the reaction products are fractionated to separate an iso-butane fraction and a normal butane fraction, the improvement which comprises subjecting at least a portion of said iso-butane fraction to thermal dehydrogenation in a pyrolysis step, recycling any remainder of said iso-butane fraction to said alkylation reaction

- zone, conducting said thermal dehydrogenation treatment under conditions of temperature and reaction time effective to convert a substantial proportion of the iso-butane to butylene while minimizing the formation of other products, recycling to said alkylation step butylene obtained as a product of said thermal dehydrogenation treatment, subjecting at least a portion of said normal butane fraction to catalytic isomerization treatment to effect conversion thereof to iso-butane, and recycling the isomerization product to said alkylation step.
5. In a process for alkylating iso-butane with butylene in an alkylation step in which iso-butane is maintained in substantial excess over butylene in a liquid acid catalyst alkylation zone and the reaction products are fractionated to separate an iso-butane fraction and a normal butane fraction, the improvement which comprises subjecting at least a portion of said iso-butane fraction to thermal dehydrogenation in a pyrolysis step, recycling any remainder of said iso-butane fraction to said alkylation reaction zone, conducting said thermal dehydrogenation treatment under conditions of temperature and reaction time effective to convert a substantial proportion of the iso-butane to butylene while minimizing the formation of other products, recycling to said alkylation step butylene obtained as a product of said thermal dehydrogenation treatment, subjecting at least a portion of said normal butane fraction to catalytic isomerization treatment to effect conversion thereof to iso-butane, and recycling to said alkylation step a mixture of normal butane and iso-butane obtained as a product of said isomerization treatment.
6. The method of preparing a high octane motor fuel which comprises catalytically isomerizing normal butane to form iso-butane, pyrolyzing at least a portion of the iso-butane thus obtained to produce butylene, and catalytically reacting butylene thus obtained with iso-butane to produce a motor fuel ingredient of high anti-knock value.
7. The method of preparing a high octane motor fuel which comprises pyrolyzing iso-butane to produce butylene, catalytically isomerizing normal butane to form iso-butane and catalytically alkylating butylene thus obtained with iso-butane produced in said isomerization step.
